DESIGN FOR SUSPENDERS

Karl Sedlacek, St. Katherines, Ontario, Canada

Application August 28, 1940, Serial No. 94,676

Term of patent 14 years

To all whom it may concern:

Be it known that I, Karl Sedlacek, a citizen of Czechoslovakia, residing at St. Katherines, in the Province of Ontario and Dominion of Canada, have invented a new, original, and ornamental Design for Suspenders, of which the following is a specification, reference being had to the accompanying drawing, forming part thereof.

The figure is a frontal elevation of the suspenders showing my new design.

I claim:

The ornamental design for suspenders, as shown.

KARL SEDLACEK.
